CALCULATING MACHINE

Carl M. F. Friden, Oakland, Calif., assignor to
Marchant Calculating Machine Company,
Emeryville, Calif., a corporation of California

Application January 14, 1928, Serial No. 246,677

12 Claims. (Cl. 235—137)

The invention relates to calculating machines adapted to perform problems in addition, subtraction, multiplication and division.

An object of the invention is to provide a calculating machine having a product register and a grand total register in which a plurality of products may be accumulated.

Another object of the invention is to provide means for simultaneously clearing the product register and transferring the values registered therein to the grand total register.

Another object of the invention, is to provide power operated means, under the control of the operator, for clearing the product register and transferring the values therein to the grand total register.

Another object of the invention is to provide means which, in its initial operation, transfers values from the product register to the grand total register and which, in its further operation, 20 operates the tens carrying mechanism of the grand total register.

A further object of the invention is to provide a tens carrying mechanism in association with the grand total register, which is operable subsequent to the introduction of the complete value into the grand total register, from the product register.

The invention possesses other advantageous features, some of which with the foregoing, will be set forth at length in the following description, in which I shall outline in full that form of the invention which I have selected for illustration in the drawings accompanying and forming part of the present specification. In said drawings, I have shown one embodiment of my invention, but it is understood that I do not limit myself to such form, since the invention, as set forth in the claims, may be embodied in a plurality of forms.

40 Referring to said drawings.
Figure 1 is a vertical transverse section through
a portion of the calculating machine, showing the
grand total register, the product register, and the
actuator for introducing values into the product
45 register.

Figure 2 is a vertical longitudinal section through the longitudinally movable carriage showing the product register and the grand total register.

50 Figure 3 is a section taken on the line 3-3
Fig. 2

Figure 4 is a section taken on the line 4-4

Fig. 2.
Figure 5 is a section taken on the line 5—5
55 Fig. 2.

Figure 6 is a section taken on the line 6-6
Fig. 2.

Figure 7 is an end view of a portion of the machine, parts of the casing being broken away and other parts being shown in section, to show the mechanism for controlling the application of power for the purpose of transferring values from the products register to the grand total register and operating the tens carrying mechanism of the grand total register.

Figure 8 is a section through the grand total register, showing the tens carrying mechanism in inoperative position.

Figure 9 is a similar view showing the tens carrying mechanism in operative position.

Figure 10 is a cross section of the grand total register, taken on the line 10-10 Fig. 11, showing the means which is set by a transitional carry of one numeral wheel to cause the operation of the tens carrying mechanism to advance the numeral wheel of the next higher order, one step.

Figure 11 is a front elevation of a portion of the grand total register, showing the tens carrying mechanism.

Figure 12 is a cross section taken on the line 12-12 Fig. 2, showing the zero resetting means associated with the product and grand total registers.

Figure 13 is a longitudinal section taken on the line 13-13 Fig. 12.

Figure 14 is a section taken on the line 14—14, Fig. 2, showing the mounting of the grand total register shaft.

Figure 15 is a section taken on the line 15-15, Fig. 2, showing the one direction clutch in the grand total register shaft.

Figure 16 is a diagrammatic representation of the driving mechanism for operating the zero resetting device of the product register and the tens carrying mechanism of the grand total register.

The invention relates to calculating machines of the type shown in my United States Letters Patent Number 1,643,710 of September 27, 1927, to which reference is hereby made for a disclosure of a complete calculating machine of this type, since features of the calculating machine not involved in the present invention are not disclosed in this application. The present invention relates particularly to the incorporation in the machine, of a grand total register, which is associated with the product register and with the means for transferring registered values from the product register to the grand total register. The machine shown in the patent and in the

present application is arranged to be driven by an electric motor, but it is to be understood, that the invention is equally well applicable to a hand driven machine. The calculating machine comprises a suitable frame upon which are arranged the various instrumentalities which cooperate to produce a complete calculating machine. The machine includes a reversible, rotary actuator 2, which is fully described in said patent, into which values are introduced, preferably by the depression of keys, and which, on rotation, transfer the introduced values to the numeral wheels of the product register, which, for the purpose of making direct action of the selected values on the figure discs of highest value possible, is disposed in parallel displaceable relation to the axis of the actuator. The product register is mounted in a carriage which is displaceable longitudinally into registry with the actuating elements of the actuator, in different numerical order.

The actuator comprises a plurality of actuating elements 3, which cooperate, on rotation of the actuator in either direction, with the intermediate wheels 4 of the product register. This register comprises a series of numeral wheels 5, each wheel being provided on one side with a gear 6 which is in mesh with its associated intermediate gear 4. Each numeral wheel 5 is provided with a transfer lever 7 which is moved to operative position by a projection 8 carried by the numeral wheels and which is returned to inoperative position by a restoring cam carried by the actuator. Tens carrying pins 9 carried by the actuator, serve to move the numeral wheel of the next higher order, one step, on rotation of the actuator when the transfer lever 7 has been moved to operative position. This is well understood in the art and is fully disclosed in my said patent above referred to. Means are provided for causing the numeral wheels 5 to move in a step by step movement and to prevent their overthrow when driven by the actuating elements 3. For this purpose, an escapement latch 12 is provided for each numeral wheel. The plurality of latches are rotatably mounted on a rod or shaft 13 and each latch is provided at one end with a tooth 14 adapted to engage between adjacent teeth of the gear 6 and at the other end, with a tooth 15 adapted to engage between adjacent teeth of the intermediate gear 4. The escapement latches are normally held in spring pressed engagement with the teeth of the gear 6, by the springs 16 seated in the rocking bar 17, the function of which will appear hereinafter. Upon rotation of the intermediate gear 4 by the actuator element 3, the escapement latch 12 is rocked, causing a step by step movement of the numeral wheel 5.

The numeral wheels 5 are rotatably mounted on a normally stationary, hollow shaft 21 (Fig. 12 and Fig. 13) in which is disposed a stationary inner shaft 22 provided with a longitudinal groove 23. Each numeral wheel has an enlarged bore and disposed in the bore is a tooth 24 which, when the numeral wheel is in zero position, is disposed in radial alinement with a hole 25 through the hollow shaft 21; the groove 23 is normally in registry with the series of holes 25, and, in each hole, there is disposed a ball 26 which, upon rotation of the outer shaft with respect to the inner shaft, is forced out of the groove in the inner shaft so that it projects beyond the periphery of the outer shaft. When the numeral wheel 5 is out of zero position, the

projected ball engages the tooth 24 and carries the numeral wheel back to zero position, at which position, the ball 25 recedes into the groove 23, thereby moving out of engagement with the tooth 24. The groove 23 and the holes 25 are formed on the upper side of the inner and outer shafts 22 and 21 respectively. The product register is reset to zero by rotating the outer hollow shaft 21 and this shaft may be rotated by hand or by an electric motor. Secured to the end of the hollow shaft 21 (Fig. 4) is a disc 28 having a notch therein in which is disposed the end of the rocking lever 29 which is secured to the end of the bar 17. The lever 29 is urged into engagement with the disc 28 by the spring 31 and, on the initial rotational movement of the disc 28, the lever 29 is rocked against the pressure of the spring 31, rocking the bar 17 and thereby moving the springs 16 therein from engagement with the escapement latch 12, thereby permitting ready rotation of the numeral wheels 5, by rotation of the zero resetting shaft 21.

Mounted in the carriage adjacent the product register is a grand total register comprising a series of numeral wheels 33, these numeral wheels preferably being in alinement with the numeral wheels 5 of the product register. The numeral wheels 33 are rotatably mounted on a normally stationary rotatable shaft 34 and each numeral wheel 33 is provided on one side with a gear 35 which is normally out of mesh with the intermediate gear 4 and which is movable into mesh with said intermediate gear, as will be set forth hereinafter. Each numeral wheel 33 is provided with a spring pressed detent 36 which engages between two adjacent teeth of the gear 35 to prevent overthrow of the numeral wheels and to cause said wheels to move with a step by step movement. The numeral wheels 33 are provided with zero resetting devices which are identical with the zero resetting devices of the product register and which comprise a tooth 37 on the inner periphery of the enlarged bore of the numeral wheels 33, the ball 38 seated in a hole in the hollow shaft 34 and the inner normally stationary shaft 39 which is provided with a longitudinal groove in which the balls are normally seated. As in the product register, the balls 38 are normally seated in the holes in the outer shaft 34 which holes are disposed along the upper side of the shaft 34, so that the balls are normally held by gravity below the outer periphery of the shaft 34. Relative movement of the shaft 34 with respect to the shaft 39, forces the balls outward so that their circular path intersects the inwardly projecting tooth 37. The grand total register numeral wheels 33 are reset to zero by rotating the outer shaft 34 while the inner shaft 39 is held stationary.

In order to transfer values from the numeral wheels 5 to the numeral wheels 33, it is necessary to bring these wheels into engagement and, in the present instance, this is accomplished by moving the grand total register bodily transversely to bring the gear wheels 35 into mesh with the intermediate gear wheels 4. To permit this bodily movement of the grand total register, the outer shaft 34, on which the numeral wheels 33 are rotatably mounted, is provided at its ends with squared portions 42 which seat in straight-sided slots 43 (Fig. 14) formed in hubs 44 and 44' which are rotatably mounted in the frame of the carriage. The hubs 44 and 44' normally stationary and the slots therein are normally parallel to a

line connecting the axes of the shafts 22 and 39. Normally, the axis of the shaft 34 is in alinement with the axis of rotation of the hubs 44, so that when the hubs are rotated, the shaft 34 is also rotated. In this normal position, the gears 35 of the grand total register are out of mesh with the gears 4.

Means are provided for moving the grand total register bodily, transversely into cooperative relation with the product register. Adjacent each end, the shaft 34 is journalled in slides 46 (Fig. 6) which are slidable in the direction of the line intersecting the axes of the shafts 22 and 39 and which slides are normally held in elevated or raised position by the springs 47. Projecting from each slide is a pin 48 which is engaged by a lever 49, the other end of which is in engagement with a cam 51 secured to a driven shaft 21 arranged in the carriage so that upon the initial rotational movement of the shaft 21, the lever 49 is rocked to move the slide 46 downward to bring the gears 35 into mesh with the intermediate gears 4. At the completion of a rotation of the shaft 21, the springs 47 return the grand total register to its normal or elevated position. The driven shaft 21 (Figs. 2 and 5) is journalled in the frame of the carriage and is provided with a gear 53 which is given one complete revolution during the operation of transferring values from the product register to the grand total register. Journalled in the frame of the carriage is a driving shaft 54 to the end of which is secured a gear 55 which is in mesh with a gear 56. Mounted on the same shaft with and secured to the gear 56, so that they all rotate in unison, are two mutilated gears 57 and 58. The gear 57 is co-planar with and is adapted to mesh with the gear 53, these two gears having the same number of teeth, in this instance ten teeth, so that the shaft 21 is given one complete rotation for each complete rotation of the gear 56. The gear 58 is co-planar with and is adapted to mesh with the gear 61 which is secured to the hub 44' which carries one end of the hollow shaft 34. In the particular construction shown herein, it is desirable that the hub 44' be given two complete revolutions for each revolution of the gear 56 and therefore, the gear 58 is provided with twenty teeth and the gear 61 is provided with ten teeth. The gears 57 and 58 are so arranged with respect to each other and with respect to the gears 53 and 61, that, upon rotation of the gear 56, the gear 57 first meshes with and rotates the gear 53 for one revolution, and moves out of mesh with the gear 53 before the gear 58 moves into mesh with the gear 61. Further, during the time that the gear 58 is in mesh with the gear 61, the gear 57 is always out of engagement with the gear 53. Values are transferred from the numeral wheels of the product register to the numeral wheels of the grand total register, by resetting the numeral wheels of the product register to zero, the movement of the numeral wheels 5 during this operation serving to transfer the values to the numeral wheels of the grand total register, through the gears 6, 4, and 35. The shaft 21, to which the gear 53 is secured, is the zero resetting shaft of the product register. The initial rotational movement of this shaft serves to move the grand total register into engagement with the product register and the further movement of this shaft serves to transfer the values from the product register to the grand total register and at the completion of one rotation of the shaft 21, the product register is moved to elevated or normal position. The tens

carrying mechanism of the grand total register, which is operated by the gear 61, is then brought into operation to carry tens into the grand total register, so that the value appearing therein is the correct accumulated value. The grand total register is provided with tens carrying means which are operated by rotation of the hollow shaft 34 and the inner shaft 39. The tens carrying members for the successive numeral wheels of the product register must necessarily be spaced apart angularly, so that they are successively brought into operation during the rotation of the shaft. I have found that in a grand total register having nine numeral wheels, that the tens carrying mechanism is fully operated by one rotation of the shaft, 15 but since it is usually desirable to provide a grand total register having at least twelve numeral wheels, I have provided means for giving the tens carrying shaft two complete revolutions, thereby providing for the operation of all of the tens carrying devices. Should more than twenty wheels be required in the grand total register, it will be necessary to so proportion the gears 58 and 61, that the shaft 34 is given three complete rotations.

Each numeral wheel 33 (Fig. 10) is provided 25 on the side opposite the gear 35 and adjacent the numeral wheel of next higher order, with a pin or projection 63. Pivoted on a shaft parallel to the shaft of the grand total register, are a plurality of arms 64 which extend into the spaces 30 between the successive numeral wheels, there being one arm associated with each numeral wheel. The arm is provided on its under surface, adjacent its inner end, with a cam tooth 65 against which the pin 63 lies, when the numeral wheel is 35 in zero position. The additive direction of movement of the numeral wheel is counter-clockwise, and, when the numeral wheel has moved nine steps in an additive direction, the projection 63 is in contact with the other side of the cam tooth 40 65. One more additive movement of the numeral wheel, causes the projection 63 to force the cam tooth 65 upward, so that in a movement of the numeral wheel from nine to zero, the arm 64 is 45 rocked upward, in which position it is temporarily retained by means comprising the spring pressed ball 64' (Figure 1) inset in the shaft supporting arm 64 and pressed against the inside of the hub of arm 64. The arm is provided on its inner end with a curved shoe 67 having a bevelled forward 50 edge 68. Under the action of the projection 63, on the numeral wheel, the shoe 67 is moved outward, substantially, radially from inoperative to operative position. Secured to the shaft 34 between each two numeral wheels is a disc 71 55 and pivoted to the disc is a lever 72 which is normally held in outward position against the stop 73 by a spring 74. The lever 72 is provided with two pins, the pin 75 projecting from one side of the lever and the pin 76 projecting from the other side. The pin 75 projects on the side of the disc which lies toward the numeral wheel of lower order and is disposed in a recess or cut-out portion in the disc. The pin 76 lies on the side adjacent the numeral wheel of next higher order and is 65 coplanar with the gear wheel 35 which is secured to said numeral wheel of next higher order. The pin 75 is normally disposed in a circular plane which lies outside the plane of the shoe 67, when the shoe is in its inner position. When the shoe 70 is moved to its outer position, however, it lies in the path of the pin 75, so that on rotation of the disc 71, the pin 75 contacts with the bevelled end 68 of the shoe, and is moved inward, moving the lever 72 and consequently the pin 76 inward. The 75

pin 16 is so disposed, that when the lever 72 is in its outer position, that the pin passes the teeth of the gear 35 and when the lever 72 is moved to its inner position, the pin 16 engages a tooth of the gear 35. The lever 72 is held depressed by the shoe 67 and the shoe is of such length that the lever is held depressed for a sufficient time to cause the pin 16 to move the gear 35 and consequently the numeral wheel 33 one step. As the pin 75 passes out from under the shoe 67, the spring 74 moves the lever 72 outward, moving the pin 16 from engagement with the tooth of the numeral wheel 35.

The disc 71 also carries means for restoring the transfer arm 64 to inner or inoperative position, after the shoe 68 thereon has functioned to cause a transitional carry to the numeral wheel of next higher order. Secured to or formed on the disc 71, preferably substantially diametrically opposite the pin 75 is a cam 78 which, on further rotation of the disc, contacts with the shoe 68 and moves the shoe inward to the inoperative position shown in Figure 10.

In transferring values from the product register to the grand total register, one or more of the numeral wheels of the grand total register will pass through zero, moving the associated shoes 67 outward. The transitional carry to the respective numeral wheels of next higher order, is accomplished by rotation of the shafts 34 and 39, the rotation of the shaft 39 being necessary in order to prevent the operation of the zero resetting means. Rotation of the shaft 34 causes rotation of the discs 71 secured thereto and such rotation causes the pins 75 to coact with the extended shoes 67, and effect the transitional carry to the numeral wheels of next higher order. The levers 72 are respectively spaced apart angularly on the successive discs so that the transitional carry is successively performed on the successive discs of increasing numerical order. The completion of the rotation of the discs brings the cam 78 into operation to return the transfer arm 64 to normal inoperative position. The shaft 34 is given one or more complete rotations depending upon the number of numeral wheels in the grand total register. The shafts 34 and 39 are yieldingly coupled together by spring pressed balls 81 carried by the shaft 39 and projecting into recesses in the shaft 34, the springs being sufficiently strong to resist the load of the tens carrying mechanism so that the balls serve to normally cause the two shafts to rotate together, but being sufficiently weak to permit rotation of the outer shaft while the inner shaft is held stationary in the zero resetting operation. As has been set forth hereinbefore, the grand total register is reset to zero by rotating the outer shaft 34 while holding the inner shaft 39 stationary.

The hub 44 in which the end of the shaft 34 is non-rotatably seated, is provided with a stub-shaft 83 journaled in the frame of the carriage and splined thereto is a spring pressed member 84 which forms part of a one direction clutch, that is, a clutch which operates to transmit movement in one direction of rotation only. The other clutch part 85 is provided with a shaft 86 journaled in the frame of the carriage and on the end of the shaft there is secured a gear 87 which meshes with a gear 88 which is secured to the shaft 89 of the crank handle 91, the shaft 34 is rotated in a clockwise direction for the purpose of operating the tens carrying mechanism and is rotated in a counter-clockwise direction for the pur-

pose of resetting the numeral wheels 33 to zero. The one direction clutch composed of the members 84 and 85 transmits rotation in a counter-clockwise direction only so that the crank handle 91 is not rotated during the tens carrying operation.

During the zero resetting operation, it is necessary that the inner shaft 39 remain stationary and means are provided whereby the initial rotational movement of the crank handle 91 locks the inner shaft 39 against rotation. Journalled within the alined hollow shafts 83 and 86 is a stub shaft 92 having a half-round end which engages a half-round end of the shaft 39, so that by holding the shaft 92 against rotation, the shaft 39 is also held against rotation. The outer end of the shaft 92 is squared or otherwise made un-round, so that it may readily be engaged by a locking mechanism. Secured to the shaft 89 (Fig. 4) is a cam 93 against which bears a pin 94 which is secured to a slide 95 having a seat 96 in its end which is adapted to engage the non-round end 97 of the shaft 92 and hold said shaft against rotation. Normally, the shaft 92 is free to rotate, but on the initial movement of the crank 91, the slide 95 is moved to cause the seat 96 to engage the ends 97 of the shaft 92 and thereby hold said shaft against rotation during the time that the crank arm is out of neutral or full cycle position.

The present machine is particularly designed for motor drive and means have been provided under the control of the operator, for causing the motor to drive the mechanism for the required time to move the grand total register into engagement with the product register for resetting the product register to zero and transferring the values therein to the grand total register, and for operating the transfer mechanism of the grand total register, and then stopping the parts in neutral or full cycle position, and this is accomplished, regardless of the longitudinally displaced position of the carriage on the frame of the machine. The driving shaft 54 of the various devices mounted on the carriage, is splined to a floating shaft 95 which is in turn splined to the driving hub 96, which is journaled in the frame of the machine, thereby providing a telescopic driving connection between the driving hub 96 and the driving shaft 54 of the carriage mechanism.

The machine is driven by a motor 102 (Fig. 16) which drives through suitable reduction gearing, to the gear 103. Secured to the shaft of gear 103 is a ratchet pinion 104 (Fig. 7) which forms part of a clutch, the other part comprising the clutch housing 105. Secured to the clutch housing is a gear 106 which meshes with a gear 107 rotatably mounted on the shaft 108 and which in turn meshes with a gear 109 which is secured to the driving hub 96 (Fig. 2). The ratchet pinion 104 is driven during the time of operation of the motor and means are provided for controlling the connection of the ratchet pinion with the gear 109. Journalled on the shaft which carries the pinion 104 is a clutch housing 105 in which is mounted a pawl 112 which is provided with a foot 113 which lies adjacent an aperture in the clutch housing. The pawl 112 is normally held out of engagement with the pinion 104 and the clutch housing is normally held stopped in full cycle position by the clutch lever 114 which extends through the aperture in the housing and engages the foot 113 on the pawl. Connected to the lever 114 is a control lever 115 which extends

shaft while said wheels remain stationary, and means for successively coupling said wheels to said actuators for rotation thereby in tens carrying operations.

5 12. In a calculating machine, a rotatable shaft, registering wheels mounted thereon, tens carrying actuators interspersed between said wheels

and operable by said shaft, means for rotating said shaft while said wheels remain stationary, and means comprising cams settable by said wheels for thereafter coupling said wheels to said actuators for rotation thereby in tens carrying operations.

CARL M. F. FRIDEN.
